ANDREW WHELDON BILES, OF GLASGOW, SCOTLAND.

TIPPING APPARATUS FOR WAGONS AND THE LIKE.

Application filed June 12, 1926, Serial No. 115,535, and in Great Britain June 25, 1925.

This invention refers to tipping apparatus for wagons and the like, hereinafter referred to generally as wagons, of the type for use in tipping wagons outwardly, particularly sideways, hereinafter referred to generally as sideways, and to effect discharge at a position which may involve outward movement sideways to an appreciable extent.

- 10 10 Tipping apparatus according to this invention comprises a bed structure, a cradle movable angularly sideways and laterally relatively to the bed structure, the cradle at its outer side being guided for movement laterally and at its inner side movable angularly sideways and laterally, and a carrier on the cradle movable angularly sideways and laterally relatively to the cradle.

The cradle at its inner side may be link supported. For instance, it may be carried at its inner side by links which for support of the cradle in its normal or horizontal position extend vertically downwards or thereabouts from pivots, and having the cradle at 25 its outer side mounted to move on guides which extend horizontally or thereabouts. With this system, in operating from the normal position, motion imparted through the links causes the cradle to be moved angularly sideways and laterally outwards relatively to the bed structure, the inner side of the cradle being raised and moved laterally outwards, the outer side being moved laterally outwards. Thus, an extreme outward 30 position sideways may be reached, in which the axis of the pivots, points of connection between the links and inner side of cradle, and points at the outer side where the cradle moves on the guides, are in alignment.

40 Further, by continued upward movement of the inner side of the cradle after the extreme outward position has been reached the outer side would be moved laterally inwards.

45 Apparatus according to this invention may be so constructed that in the process of its operation little or no upward displacement of the load to be dealt with need occur.

Some examples of construction according 50 to this invention will now be described with reference to the accompanying drawings, in which:—

Figure 1 is an end view and Figure 2 is a plan of one form of construction with a wagon shown in its normal position, and

Figures 3, 4, 5, 6 and 7 are diagrams illustrating the process of operation.

Figure 8 is an end view illustrating another form of construction, Figure 9 is a sectional view illustrating part of Figure 8, 60 and Figures 10, 11, 12 and 13 are diagrams illustrating the process of operation.

In the forms of construction illustrated the apparatus comprises a bed structure A, a cradle B mounted on the bed A, a carrier C mounted on the cradle B, a platform D on the carrier C having rails 2 for a wagon E to run on.

With the constructions illustrated the process of operation involves actions as follows:—In the normal position, the platform D is horizontal and the wagon E is supported on the rails 2, and for the process of tipping a turning movement of the wagon angularly sideways is imparted which may extend generally beyond 90° up to say about 135°, in the process of which lateral movement is imparted which transfers the wagon from its normal position to a position outwards which may be well clear of the run of the fixed rails 3 of the main track. In the process of operation support, say, by a side buffer 4 mounted on the carrier C, is initially afforded to the wagon at its side, its outer side, towards which it is being moved and support thereby afforded to the wagon in the second portion of its movement, and at a later stage in the process of operation support is afforded to the wagon at its top by means such as a retaining bar 5 on cradle B, in addition to the support afforded at its side.

A mounting for the platform D on the carrier C may be such that in the normal position a firm support is provided for the platform on the carrier and as the turning proceeds a bearing which permits the platform to turn on the carrier comes into operation.

The cradle B may have an axle or trunnions provided with rollers 6 to run on guides 7 which extend laterally. The guides 7 may be horizontal or inclined. In the examples illustrated, the guides 7 are shown extending downwardly to the extreme outward position at the side. The cradle B may be moved angularly sideways and laterally relatively to the bed A by means attached at its inner side which for movement to the extreme outward position operate to 100

raise the inner side and simultaneously move the cradle outwards. For example, lever arms 8 pivoted to the inner side of the cradle B by horizontal pivots at 9, may be provided mounted to turn about a horizontal axis 10 at a position above the inner side of the cradle B, say, nearly vertically above. The lever arms 8 may be provided with toothed racks 11 concentric to the axis 10 and be turned by pinion gear.

In the form of construction illustrated at Figures 1 and 2, see also Figures 3, 4, 5, 6 and 7, the platform D is mounted normally to rest upon the carrier C, and, when the carrier is moved angularly sideways, to turn on an axis at 12. The bearing for the carrier C on the cradle B in this construction is of the rocker type comprising two races, a race 13 on the upper surface of the cradle B, and a race 14 on the under surface of the carrier C. These races may be plain, or be formed so as to prevent slipping. For instance, as shown at Figure 1, they may be toothed. With this form of construction the movements of the carrier C on the cradle B are of a rolling nature.

In Figures 8 and 9, see also Figures 10, 11, 12 and 13, a method is illustrated in which the movements of the carrier C and cradle B are synchronized. In this case the carrier C is connected to the cradle B by means of links, two pairs, each pair comprising a link G pivoted to the cradle at 15 and to the carrier at 16, and a link H pivoted to the cradle at 17 and to the carrier at 18. The link H, see Figure 8, is provided with a segmental toothed rack K the axis of which is 17, and on the axis 17 a member L is mounted provided with a segmentally toothed rack L¹, corresponding to K, and with a second rack L² in gear with a pinion P which rotates with wheel 6, wheel 6 being toothed to engage with guide 7 toothed correspondingly. Carried by bar 5 is a toothed wheel R adapted in one position to mesh simultaneously with the two racks K and L¹. The wheel R is movable laterally to enable it to be taken out of mesh from the racks K and L¹. For this purpose the wheel 8, see Figure 9, may be carried by an axle movable laterally in a guide and acted on by a spring 18 which tends to thrust the wheel into mesh with the racks K and L¹. Removal from mesh is effected by a thrust beam S adapted to be acted on by the top of the wagon E as it meets the bar 5. In the normal position the wheel R is in mesh with the two racks K and L¹, and as the cradle B is moved angularly sideways and laterally wheel R remains in mesh until removed by the thrust beam S being acted on by the top of the wagon. Movements beyond this position are performed with the wheel R out of mesh, the wheel R again meshing with racks K and L¹

when the top of the wagon passes away from the bar 5. Thus, by the gearing and link mechanism movements such as indicated by the diagrams, Figures 10, 11, 12 and 13, must be performed, and in the process of operation the movements of the carrier C on the cradle B would be synchronized. Thus, movements between the normal position and position when the top of the wagon meets or leaves the bar 5, would always be similar, 75 and in conformity with progressive positions of the wheel 6 which is toothed on the guide 7 which is correspondingly toothed.

The apparatus may be constructed to provide a way for entry of the wagons free from overhead obstruction. The way provided may be such as to give a through passage, whereby, for example, loaded wagons may be moved in at one end, discharged, and passed out empty at the opposite end. 85

I claim:—

1. Tipping apparatus for wagons comprising a bed structure, a cradle movable angularly sideways and laterally relatively to the bed structure, the cradle at its outer side being guided for movement laterally and at its inner side movable angularly sideways and laterally, and a carrier on the cradle movable angularly sideways and laterally relatively to the cradle. 95

2. Tipping apparatus for wagons comprising a bed structure, a cradle movable angularly sideways and laterally relatively to the bed structure, the cradle at its outer side being guided for movement laterally, link support for the cradle at its inner side for movement angularly sideways and laterally, and a carrier on the cradle movable angularly sideways and laterally relatively to the cradle. 100

3. Tipping apparatus for wagons comprising a bed structure, a cradle movable angularly sideways and laterally relatively to the bed structure, the cradle at its outer side being guided for movement laterally and at its inner side movable angularly sideways and laterally, a carrier on the cradle movable angularly sideways and laterally relatively to the cradle, a platform on the carrier movable angularly relatively to the carrier, and rails on the platform for a wagon to run on. 110

4. Tipping apparatus for wagons comprising a bed structure, a cradle movable angularly sideways and laterally relatively to the bed structure, the cradle at its outer side being guided for movement laterally and at its inner side movable angularly sideways and laterally, means on the cradle for support of a wagon at its top, a carrier on the cradle movable angularly sideways and laterally relatively to the cradle, and means on the carrier for support of a wagon at its outer side. 120

5. Tipping apparatus for wagons comprising a bed structure, a cradle movable angu- 125

- iarly sideways and laterally relatively to the bed structure, the cradle at its outer side being guided for movement laterally and at its inner side movable angularly sideways and laterally, a retaining bar on the cradle for support of a wagon at its top, a carrier on the cradle movable angularly sideways and laterally relatively to the cradle, and a buffer on the carrier for support of a wagon at its 10 outer side.
6. Tipping apparatus for wagons comprising a bed structure, a cradle movable angularly sideways and laterally relatively to the bed structure, guides on the bed structure for the cradle at its outer side for movement laterally, link support for the cradle at its inner side for movement angularly sideways and laterally, a retaining bar on the cradle for support of a wagon at its top, a 15 carrier on the cradle movable angularly sideways and laterally relatively to the cradle, a buffer on the carrier for support of a wagon at its outer side, a platform on the carrier movable angularly relatively to the carrier, and rails on the platform for a wagon to run on, for the purposes set forth.
7. Tipping apparatus for wagons comprising a bed structure, a cradle movable angularly sideways and laterally relatively to the bed structure, guides on the bed structure, 20
- rollers on the cradle at its outer side to run on the guides, link support for the cradle at its inner side for movement angularly sideways and laterally, a retaining bar on the cradle for support of a wagon at its top, a carrier on the cradle, a race on the under surface of the carrier, a race on the upper surface of the cradle, a buffer on the carrier for support of a wagon at its outer side, a platform on the carrier movable angularly relatively to the carrier, and rails on the platform for a wagon to run on, for the purposes set forth.
8. Tipping apparatus for wagons comprising a bed structure, guides on the bed structure, a cradle, rollers on the cradle at its outer side to run on the guides, link support for the cradle at its inner side for movement angularly sideways and laterally, a retaining bar on the cradle for support of a wagon 25 at its top, a carrier on the cradle, a toothed race on the under surface of the carrier, a toothed race on the upper surface of the cradle, said toothed races intermeshing, a buffer on the carrier for support of a wagon at its outer side, a platform on the carrier movable angularly relatively to the carrier, and rails on the platform for a wagon to run on, for the purpose set forth.

ANDREW WHELDON BILES.
